Patented Sept. 28, 1926.

UNITED STATES PATENT OFFICE.

HAROLD H. COLLINS, OF CINCINNATI, OHIO.

REFLECTING ELECTRIC LAMP.

Application filed September 15, 1922. Serial No. 588,387.

This invention relates to electric lamps of the filament type and has as one of its primary objects to provide a lamp of this type in which light rays which would ordinarily be projected toward the base of the lamp and be spent without any appreciable illuminating effect, will be reflected in such a manner as to obtain the full benefit therefrom.

10 Generally speaking the invention contemplates providing within the bulb of an electric lamp of the filament type, a reflector so positioned as to reflect those light rays emanating from the filament which would otherwise be projected toward the base of the lamp without any practical benefit, and it is another important object of the invention to provide the reflector with a reflecting surface of such contour as to obtain the best 15 results.

Another important object of the invention is to provide a novel arrangement of the reflector and a novel means for supporting the same and the filament such as to properly 20 relatively position these parts in the most stable and substantial manner and to obtain the maximum benefit from the light rays emanating from the filament.

In the accompanying drawings:

30 Figure 1 is a perspective view of an electric filament lamp constructed in accordance with the invention;

Figure 2 is a vertical axial sectional view therethrough taken substantially on the line 35 2—2 of Figure 1 looking in the direction indicated by the arrows.

The lamp embodying the invention comprises the usual bulb 1 having the attaching base 2 of any of the usual types and with 40 the terminals of which base are connected the conductor wires or leads 3 which are associated with the stem of the lamp indicated in general by the numeral 4. As is usual, this stem is formed of glass and united in the 45 usual manner to the base 2, and throughout the upper portion of its length it is tubular as indicated by the numeral 5 and houses the upper portions of the conductor wires or leads 3, these wires being suitably spaced by being passed through spaced perforations in a disc of insulating material 6 housed within the said tubular portion of the stem. The lower portion of the stem is solid and indicated by the numeral 7, and 55 the wires 3 are led laterally in opposite directions through the wall of the tubular por-

tion 5 of the stem immediately above the juncture of said portion with the upper end of the portion 7, and are thence led downwardly at opposite sides of the said portion 60 7 of the stem, being spaced and retained in place by a disc 8 of insulating material through which their upper portions are passed and which disc is mounted upon the solid portion 7 of the stem 4.

65 The reflector embodying the invention is indicated in general by the numeral 9 and the same is supported at the lower end of the solid portion 7 of the stem 4. The reflector 9 comprises a body of substantially 70 the form shown in the drawings and having the general shape of a partly hollow cone, the exterior surface of which constitutes the reflecting surface and is indicated 75 by the numeral 10. This surface has a substantially anticlastic conical contour, that is to say it is circumferentially convex and longitudinally concave. The reflecting surface may be provided in any of the customary ways and the reflector body 9 as a whole 80 may be integrally connected with the said lower end of the stem 7, as for example, by being integrally molded if it, like the stem, is made of glass, the stem being in any event united to the body centrally of the depression in its base which renders it partly hollow, and being in axial alinement with said body. It will also be observed that the body 9 is supported within the bulb 85 with its base presented toward the attaching base 2 of the plug and with its apex, indicated by the numeral 11, presented toward the tip end of the bulb.

90 The wires 3 are led through the body 9 of the reflector by being molded therein, or inserted through openings formed therein, as indicated by the numeral 12, and are brought toward each other with their ends located as close to each other as is practical. The ends of the portions 12 of the conductor 95 wires or leads 3 are electrically connected with the ends of an open annular filament 13. The filament 13, due to the close proximity of its ends, describes substantially a complete circle and the filament is supported 100 in a plane at right angles to the axis of the stem 4 and reflector body 9 and surrounds the said body on a line substantially diagonally opposite the central circumferential line of the reflecting surface 10. A number 105 of wires 14 are preferably employed in supporting the filament 13, the said wires being 110

anchored at their lower ends to the filament at suitable intervals as at 15 and being extended upwardly past and united to or embedded in the edge or peripheral portion of 5 the base of the reflector body 9 and above said base being directed inwardly at an angle as at 16 and embedded in or united to the solid portion 7 of the stem 4.

From the foregoing description of the invention it will be evident that those rays emanating from the filament 13 and which would ordinarily be projected upwardly and inwardly or in a more or less upward direction, will not be expended without benefit 10 inasmuch as they will be reflected back from the surface 10 of the reflector and projected with the other rays emanating from the said filament. It will also be evident that inasmuch as the gap between the ends of the filament is not of appreciable width or at least 15 is no greater than is practical, there will be no presence of a "dark side" when the lamp is energized and in fact the filament may be considered as extending continuously about 20 the reflector body.

Having thus described the invention, what is claimed as new is:

1. In an electric lamp, in combination, a bulb having an attaching base, a stem leading 30 from said base within the bulb, a reflector body of a conical form positioned within the bulb and united to the end of the supporting stem in a concentric position and with its base presented toward the 35 said attaching base of the bulb and its apex presented toward the tip end of the bulb, conductor wires associated with the stem and extending through the said reflector body and beyond the outer surface thereof with 40 their ends located in relatively close proximity, an open annular filament electrically connected at its ends with the said ends of the conductor wires to receive current therefrom, the said filament surrounding the reflector body in a plane above the apex thereof, and supporting wires radiating from the 45 stem above the reflector body and extending downwardly past the periphery thereof and united thereto and at their lower ends united 50 to and supporting the said filament.

2. In an electric lamp, in combination, a bulb having an attaching base, a stem lead-

ing from said base within the bulb, a reflector body of a conical form positioned within the bulb and united to the end of the supporting stem in a concentric position and with its base presented toward the said attaching base of the bulb and its apex presented toward the tip end of the bulb, conductor wires associated with the stem and 55 extending through the said reflector body and beyond the outer surface thereof with their ends located in relatively close proximity, an open annular filament electrically connected at its ends with the said ends of the conductor wires to receive current therefrom, the said filament surrounding the reflector body, and supporting wires radiating from the stem above the reflector body and extending downwardly past the periphery thereof and united thereto and at their lower ends united to and supporting the said filament, the reflector body having a reflecting 60 surface of anticlastic conical contour.

3. An electric lamp comprising a bulb 75 having an attaching base, a stem of glass anchored to the base and extending within the bulb longitudinally thereof, a disc supported by and surrounding said stem and of insulating material, a reflector body of 80 conical form supported at the end of the said stem, the said reflector body having a reflecting surface of anticlastic conical contour, supporting wires radiating from the stem above the reflector body and having 85 portions extending downwardly about and past the periphery of the said body in contact therewith whereby to brace the said wires against vibration, an open annular filament supported by the lower ends of the 90 said supporting wires in position surrounding the reflecting surface of the reflector body, the ends of the filament being located relatively close together and the filament being located above the lower end or apex 95 of the reflector body, and conductor wires led downwardly through the said stem, outwardly therefrom in opposite directions and through the insulating disc, the wires being led through the wall of the reflector body 100 and electrically connected with the ends of the filament.

In testimony whereof I affix my signature.
HAROLD H. COLLINS. [L. S.]
